US00D533499S

(12) **United States Design Patent** (10) Patent No.: **US D533,499 S**
(45) Date of Patent: **** Dec. 12, 2006**

(54) **BATTERY CHARGER FOR A CELLULAR PHONE**

(75) Inventor: **Takeshi Suzuki**, Tokyo (JP)

(73) Assignee: **Kabushiki Kaisha Toshiba** (JP)

(**) Term: **14 Years**

(21) Appl. No.: **29/235,788**

(22) Filed: **Aug. 8, 2005**

(30) **Foreign Application Priority Data**

May 25, 2005 (JP) 2005-015015

(51) **LOC (8) Cl. 13-02**

(52) **U.S. Cl. D13/108**

(58) **Field of Classification Search** D13/107-110,
D13/118-119, 184; D14/251, 253, 432, 434;
320/107-115

See application file for complete search history.

(57) **CLAIM**

The ornamental design for a battery charger for a cellular phone, as shown and described.

DESCRIPTION

FIG. 1 is a front, top and right side perspective view of a battery charger for a cellular phone, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a right side elevational view thereof showing the state in which the upper case and the lower case are separated.
